[57] ABSTRACT

A completely electronic taximeter has a first storage which has sufficient capacity for storing all variables required for calculating an individual fare and for storing totals required for determining the payment of the taxi driver. During operation of the taximeter the variables referring to the individual fare are transferred from the first storage to a buffer storage. Synchronizing means transfer the contents of the buffer storage in sequence to corresponding indicator elements. Although each indicator element is energized only briefly the repetition rate is sufficiently high to cause a constant visual indication. The capacity of the buffer storage is only large enough to store the values required for such indicator.

ELECTRONIC TAXIMETER HAVING SERIALLY ENERGIZED INDICATOR MEANS

BACKGROUND OF THE INVENTION

This invention relates to electronic taximeters. Specifically it relates to electronic taximeters wherein measuring elements furnish pulse sequences as a function of the distance travelled and the waiting time incurred. Pulse sequences separately or in combination are then used to compute the fare. The computation is carried out by a computer and storage means.

In known electronic taximeters the pulses signifying waiting time and the pulse sequence signifying distance travelled are applied to a circuit which selects only the faster pulse sequence for determining the fare. A countdown device is then furnished following the above-mentioned selector circuit, to furnish output pulses for a given number of input pulses, that is the fare rate is taken into consideration. The output pulses may then be applied to a mechanical or electronic indicator means.

In another known arrangement, a binary counter serves to countdown the pulses as mentioned above and an electronic indicator is mentioned. Further, two individual counters are furnished, one of which is constantly connected to the indicator means and may be reset, while the other operates continuously and is not reset until a certain key is activated. The latter counter serves to furnish an indication of the total fare collected, for example during the day. After the above-mentioned key has been activated, this total is transferred to the indicator and the account in the counter is extinguished.

In the first above-mentioned embodiment, the total values are stored in mechanical counters. These additional mechanical counters require additional expense which makes such taximeters economically unfeasible. However, of course, such totals must be available in order that the pay of the taxi driver may be correctly determined.

In the second above-mentioned known arrangement, there is no mention made as to how other totals are being stored. Probably mechanical counters are also considered here.

SUMMARY OF THE INVENTION

In a taximeter in accordance with the present invention, measuring elements furnish pulse sequences indicative of the distance travelled and the elapsed waiting time. A computer and storage means has a storage which has a capacity sufficient for storing all variables required for computing the individual fares, and further for computing totals required for determining the pay of the taxi driver. An electronic indicator means is furnished which is connected to the above-mentioned storage through a buffer storage, the capacity of the buffer storage corresponding to the capacity of the indicator means. The indicator means has a plurality of indicator elements. While the taxi is in operation, synchronizing means transfer the contents of buffer storage locations sequentially to corresponding indicator elements.

In accordance with a preferred embodiment of the present invention, the indicator means are divided into a first and second portion. The first portion serves to indicate the fare while the taximeter is in operation, while the second portion serves to indicate the addi-

tional charges incurred under the same conditions. When the taximeter is not operative, selector elements are available which, upon activation, cause the transfer of selected totals from the storage of the storage and computer means, through the buffer storage and into the indicator means.

The above-described arrangement has the advantage relative to the known arrangements that only one indicator means is required for indicating both the individual fare values and the final totals. Further, due to the fact that each indicator element is only briefly activated during each cycle, relatively little power loss is incurred in the indicator means.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings.

BRIEF DESCRIPTION OF THE DRAWINGS

FIG. 1 is a generalized block diagram showing a taximeter in accordance with the present invention;

FIGS. 2 and 2a is a circuit diagram of the constant furnishing means;

FIG. 3 is a circuit diagram of the indicator means, including associated storage means in block diagram form;

FIG. 4 is a more detailed block diagram of the computer and storage means;

FIG. 5 is a more detailed block diagram of the measuring means; and

FIG. 6 is an additional block diagram of the overall taximeter, as embodied in a highly integrated circuit form.

DESCRIPTION OF THE PREFERRED EMBODIMENTS

A preferred embodiment of the invention will now be described with reference to the drawings.

The major components of the electronic taximeter are shown in block diagram form in FIG. 1. The taximeter comprises a computer and storage means 1, an indicator means 2, control circuit means 3, switching circuit means 4 for controlling the input and output operations and an external constant furnishing means 5 which furnishes constants corresponding to and derivable from predetermined fare rates.

The control circuit means 3 comprise input register 6 which is connected to input lines e1-e6 (FIGS. 1+5). Input line e1 receives a pulse sequence which corresponds to the pulse sequence signifying the waiting time or the distance travelled, depending upon which has the higher rate. The pulses signifying the actual distance travelled are received on input line e5. The pulses received on this line may already have a rate reduced in accordance with the desired fare rate. This can, for example, be accomplished by using photoelectric distance measuring means wherein the number of perforations in a disk through which light is transmitted from a light source to a receiver varies in accordance with the desired fare rate. It might be stated in further explanation here that, by fare rate, is meant an incremental distance after which the indicator indicating the taxi fare is to be advanced. For example:

In accordance with a first fare rate the distance increment may correspond to 200 meters.

In accordance with a second fare rate the distance increment may be 150 meters.

In accordance with a third fare rate the distance increment is 100 meters, while in accordance with a fourth fare rate the distance increment is 50 meters.

In order to achieve a particularly exact measurement, it is desirable that, at each fare rate, the particular distance increment is represented by the same number of pulses. Thus, for example, 1,200 impulses may be generated for each distance increment. Thus, for the first fare rate, six pulses are generated per meter, for the second fare rate, eight pulses are generated per meter travelled, for the third fare rate, twelve pulses per meter, and for the fourth fare rate, 24 pulses per meter.

The photoelectric measuring means, if the shaft is driven in such a manner that one rotation corresponds to one meter travelled, has disks having six holes for the first fare rate, eight holes for the second fare rate, 12 holes for the third fare rate and 24 holes for the fourth fare rate. Under these conditions, any pulse received at the input on line e_5 would directly signify a predetermined fare.

Instead of the arrangement mentioned above, the pulses at the input e_5 may correspond only to a particular distance travelled. Under these conditions one pulse may for example signify one-tenth of a meter travelled. In this case the fare increase must be computed by applying constants corresponding to the desired fare rate when computing the fare as a function of the pulses on line e_5 . This is the situation which will be described herein, since it constitutes the preferred embodiment of the present invention.

The pulses received on line e_1 are pulses selected by the circuit 7 which furnishes the pulse sequence corresponding to the time or distance pulse sequence which has the greatest rate. This circuit will be described in greater detail with reference to FIG. 5. The pulses received on line e_2 signify the distance travelled, whether the taxi is or is not occupied. It must be noted that the total distance travelled must be available to the taxi driver's employer. This value is normally indicated in mechanical taximeters in a separate counter which counts the total number of kilometers travelled by the taxi. The mechanical taximeters of course also have indicators which indicate the total distance travelled by the taxi in an occupied, that is in a passenger carrying mode. Thus, for example, it may be desirable to apply one pulse to line e_2 for each 100 meters travelled by the taxi. This may be accomplished externally by counting down the pulses applied to line e_5 . Alternatively, it may be done internally within the taximeter in such a manner that for each 1,000 pulses which are applied at input e_5 , one pulse is applied to input e_2 .

Timing pulses which indicate waiting time to be charged to the passenger are received on line e_3 . This line is connected to a timing pulse generator, for example an oscillator which has a frequency of 1 KHz. It should be noted that the so-received timing pulses are not applied directly to stage 7, but are first modified by the control circuit 3 in accordance with constants furnished by the constant furnishing means 5. Thus the charge for the waiting time, too, may be adjusted in accordance with predetermined fare rates.

Synchronizing pulses are received on line e_{10} which are also derived from an electronic oscillator. The syn-

chronizing means furnish the synchronizing pulses which may have a frequency of anywhere from 100 KHz to a MHz and which serve to synchronize the whole taximeter system. The synchronizing pulses are fed into a shift register 8.

The computer and storage means 1 comprise the storage means 9 and the computer means 10 which will be described in detail with reference to FIG. 3. The indicator means 2 comprise, in the main, a buffer storage 11, a counter 12, a decoding arrangement 13 and two separate indicator sections 14 and 15. The construction and functioning of the indicator 2 will be described in detail with reference to FIG. 3.

Block 4 of FIG. 1 comprises manually activatable switching circuit which comprises an input keyboard 16 having keys for initiating input and output operations. Specifically, keys 17 function for input operations as for example "taxi unoccupied," fare rate 1, fare rate 2, fare rate 3, fare rate 4, cash, and additional charge, while keys 18 control the output operations as for example to initiate the indication of the "total distance travelled with taxi occupied," total distance travelled occupied or otherwise," etc. Keys 17 and 18 activate contacts which are coded in a matrix 19 which may for example be a diode matrix. The output of the matrix may be a 4-bit binary code which furnishes signals which are stored in a register 20. The contents of register 20 may be transferred to control circuit 3 when required. Of course it goes without saying that instead of the keys shown, input and output operations may be initiated by other switching circuit means, as for example rotary switches. Such rotary switches would initiate the different functions in accordance with the angular positions thereof. Thus for example a first rotary switch 25 may be used to replace keys 17 while a second rotary switch may be used to replace keys 18.

FIGS. 2 and 2a show the circuit diagram of the constant furnishing means. The constant furnishing means has a constant furnishing input receiving address signals on lines a_1-a_6 . Lines a_1-a_6 are the output lines of a counter 25 which also controls the addressing of the first storage means, namely storage 9 of FIG. 1. The code combination which appears at the output of counter 25 energizes selected ones of lines a_1-a_6 . This is applied to a decoding arrangement 21 whose output is furnished on lines $e_{00}-e_{45}$. Specifically, lines $e_{00}-e_{45}$ are energized sequentially within each cycle of operation of the taximeter. The output of the constant furnishing means is supplied on lines i_1-i_4 . These constants are applied to the computer and storage means. The constant furnishing means comprise printed circuit cards 22 and 23 which are interchangeable and may have any desired configuration. For example the connections between input lines e_{00} to e_n and the output lines i_1-i_4 may be made by solder joints, diodes, screw connections, etc.

A preferred embodiment of the constant furnishing means will now be described with reference to FIGS. 2 and 2a.

As is shown in FIGS. 2 and 2a a plurality of AND-gates $U_{10}-U_n$ have inputs connected to input lines e_0-e_n and output lines connected to decimal coded lines Z_0-Z_9 . It should be noted that not all input lines e have an AND-gate connected to them. For example, lines $e_{43}-e_{45}$ are directly connected to the decimal coded lines. The output lines of AND-gates $U_{10}-U_{16}$ are labelled d_1-d_7 respectively, the output lines of AND-

gates U17-U20 are labelled v_1-v_4 respectively, the output lines of AND-gates U21-U24 are labelled w_1-w_4 , respectively, the output lines of AND-gates U25-U28 are labelled x_1-x_4 , respectively, the output lines of AND-gates U29-U32 are labelled y_1-y_4 , respectively, while the output lines of AND-gates U33-U36 are labelled d_8-d_{11} , respectively. The above-mentioned output lines of the AND-gates are arranged in a vertical direction and therefore intersect the decimal coded lines Z0-Z9 which extend in a horizontal direction. At desired points of intersection, an electrical connection is made, for example, by soldering as mentioned above. Alternatively, the output lines of the AND-gates may be on the front side of the circuit board, while the decimal coded lines may be on the rear side of the circuit board and holes are provided in the circuit board at the point of intersection. The desired connections are then made by means of screws. Once such a connection has been established, energization of one of the output lines of AND-gates results in a corresponding energization of one of the decimal coded lines. Further, a decoding arrangement 24 is situated on the circuit board 22. This converts the one-out-of-ten coding existing on the decimal coded lines to a 4-bit binary code. The output of the decoder 24, namely the constant in a 4-bit binary code, is then connected to the computer means 10. Further shown in FIG. 2 is a flip-flop FF10 which may be in a OI or a IO state. The two flip-flop states correspond, respectively, to the condition of "fare I" and "fare II" in the taximeter. These terms will be explained in more detail below. It should only be noted here that when flip-flop FF10 is in the IO state, AND-gates U10-U14, as well as AND-gates U33-36 are in a conductive state, while, when flip-flop FF10 is in the OI state, AND-gates U15 and U16 are conductive. Thus when inputs $e_{00}-e_n$ are activated in turn by the decoder 21, the corresponding AND-gates furnish a signal at the corresponding AND-gate output line, which signals are transmitted, as described above to the decimal coded lines Z0-Z9. A corresponding constant thus appears on lines i_1-i_4 .

It should further be noted that on circuit board 23, AND-gates U17-U32 are further energized in dependence upon four conducting lines t_1-t_4 . These conducting lines are externally connected to keys 17, and, specifically, to keys T1, T2, T3 and T4 which, individually, indicate fare rates 1, 2, 3, and 4. Conducting line t_1 is connected to one input each of AND-gates U17 to U20, conducting line t_2 is connected to one input of each of AND-gates U21-U24, conducting line t_3 is connected to one input each of AND-gates U25-U28, conducting line t_4 is connected to one input each of AND-gates U29-U32. As shown in FIGS. 2 and 2a, the second inputs of AND-gates U17-U32 are connected to the outputs e_{05} , e_{06} , e_{07} and e_{08} of the decoder 21. Thus as soon as T1 is closed, AND-gates U17-U20 become conductive and, upon activation of lines e_{05} to e_{08} by the decoder 21 furnish pulses sequentially to the decimal coded lines Z0 to Z9 in accordance with the connections previously made. AND-gates U21 to U24, U25 to U28 and U29 to U32 are also connected to conductors e_{05} to e_{08} . Thus conducting lines v_1-v_4 carry the pulses for fare rate 1, lines w_1-w_4 carry the pulses for fare rate 2, lines x_1-x_4 the pulses for fare rate 3 and lines y_1-y_4 the pulses for fare rate 4. Since four separate fare rates are not required in a great many taximeters, the printed circuit plate 23 may be limited to, for

example, only lines v_1-v_4 if only one fare rate is to be implemented, or lines v_1-v_4 and w_1-w_4 if two fare rates are required. This is also the reason why part of the circuitry is on a separate printed circuit board, namely printed circuit board 23.

A discussion of at least part of the constants which are furnished by printed circuit boards 22 and 23 will now follow. The number and type of constants can change with the fare rate. For example, one of the constants is the base fare, that is the fare which is indicated on the taximeter as soon as it is put into operation. This is the fare which each passenger must pay, independent of the actual distance travelled. Let it be assumed that this constant, namely the base fare, is to be supplied via lines e_{00} to e_{04} . Further, let it be assumed that this base fare is \$1.25. During each operating cycle of the taximeter, pulses are applied to lines a_1 to a_6 which, in their combination, serve to energize input lines e_{00} to e_{04} sequentially. When line e_{00} is energized, a pulse is furnished through AND-gate U10, line d_1 and line Z5 which causes the output of decoder 24 to furnish the following pulse combination:

$$(2^0) \quad (2^1) \quad (2^2) \quad (2^3) \\ i_1 = 1 \quad i_2 = 0 \quad i_3 = 1 \quad i_4 = 0$$

When this "5," which corresponds to the last place in the base fare of \$1.25, has been processed, the input e_{01} is energized by a corresponding pulse combination on lines a_1-a_6 . As a result of energization of line e_{01} , AND-gate U11 furnishes a pulse to line d_2 which, via line Z2 causes the following pulse combination to appear at the output of decoder 24:

$$(2^0) \quad (2^1) \quad (2^2) \quad (2^3) \\ i_1 = 0 \quad i_2 = 1 \quad i_3 = 0 \quad i_4 = 0$$

After this value, which corresponds to the "2" in the base fare of \$1.25, has been processed, the numeral "1" is similarly processed by energization of line e_{02} .

Energization of lines e_{03} and e_{04} causes corresponding zero values to appear at the output of decoder 24, that is lines i_1-i_4 all carry zeros. This of course is due to the fact that only three digits are contained in the base fare. It should be noted that for the above operation to take place, flip-flop FF10 must be in the IO state. Flip-flop FF10 in actual practice is a part of the control circuit 3 and has been added to the constant furnishing means of FIG. 2 only for purposes of clarity.

The reason for the different states of flip-flop FF10 will now be explained. Flip-flop FF10 is in the IO state when the base fare is being indicated on the indicator means, but when the distance or waiting time which is paid for by the base fare has not yet expired; flip-flop FF10 is in the OI condition, after the service rendered to the passenger, is equal to the base fare. Thus, when the flip-flop is in the OI state, the normal advance of the indicator corresponding to the fare rate in force has to take place.

It might be noted here in addition that the base rate is actually an equivalent of the increment required to advance the taximeter. For example, to remain with the given example, the base rate of \$1.25 may be equal to the fare increment which is, for example, based on a 200 meter distance for a 20 second waiting time or a mixture of both. However, it is equally possible, that the base rate is the equivalent of an integral multiple of the fare increment or a fraction thereof. For example,

the indicated fare may advance in steps of \$0.25. The base rate of \$1.25 is to pay for a distance travelled of 500 meters or an equivalent waiting time. Then the base rate covers a distance equal to two and one-half times the distance for a fare increment or the equivalent waiting time. The distance equivalent to the base fare (500 meters in the above example) is normally referred to as the initial distance, even though, as explained above, not only an initial distance but a corresponding waiting time may be involved.

In order to take account of all these factors, it is necessary that constants be furnished which correspond to the base rate, to the distance increment for which the fare is advanced under normal conditions and for the initial distance, that is the distance which is paid for by the payment of the base fare.

Thus the base fare is first entered through lines $e00$ to $e04$ and the individual fare increments are then also transmitted by energizing these lines, so that the total fare comprises the base fare in addition to the fare increments. After the taxi has rendered a service corresponding to the base fare, flip-flop $FF10$ is switched to the OI state causing AND-gates $U15$ and $U16$ to become conductive. The other inputs of AND-gates $U15$ and $U16$ are connected to lines $e00$ and $e01$ respectively. Thus the fare increments are transmitted via lines $e00$ and $e01$ after flip-flop $FF10$ has changed its state. Thus, in the example shown in FIGS. 2 and 2a, a sequential energization of lines $e00$ and $e01$ when flip-flop $FF10$ is in the second state, causes the constant of \$0.25 to appear on output lines $i1-i4$. Thus lines $e00$ to $e04$ are used twice, that is first to furnish the constant corresponding to the base fare and later to furnish the constant signifying the value of the fare increment.

Output lines $e05$ to $e08$ of the decoder 21 are also utilized more than once, as is evident with the description of the printed circuit board 23 which is given above. Each line $e05$ to $e08$ allows the specification of one numeral for each fare rate $T1$ to $T4$. These fare rates may be the following:

Fare rate 1 — 200m — 2,000 pulses.

Fare rate 2 = 150m = 1,500 pulses.

Fare rate 3 = 100m = 1,000 pulses.

Fare rate 4 = 50m = 500 pulses.

If the number of pulses is reduced by a factor of 100 to 1 either previously or after the constant is furnished, then fare rate 1 corresponds to a pulse reduction rate of 20 to 1, fare rate 2 to a pulse reduction rate of 15 to 1, fare rate 3 to a pulse reduction rate of 10 to 1 and fare rate 4 to a pulse reduction rate of 5 to 1.

The connections between the vertical conducting lines $v1$ to $v4$ and the horizontal lines $Z0$ to $Z9$ on printed circuit board 23 are indicated by the circle.

A further constant, which has been defined above, is in the initial distance. This, too, must be furnished by constant furnishing means 5 . For this purpose lines $e09$ to lines $e12$ are energized and furnish, over AND-gates $U33$ to $U35$ and lines $d8$ to $d11$ the number "250," at the output of the constant furnishing means. As previously explained, this number corresponds to the initial distance.

A further constant which must be furnished by constant furnishing means 5 , is the constant required for stepping down the repetition rate of the waiting time

pulses. This is furnished by energization of lines $e43$ to $e45$. As will be explained in more detail later on, the pulses which are supplied on line $e3$ must be reduced in frequency by a ratio of 10 to 1. Under these conditions, 200 meters of travelled distance correspond to a waiting time increment of 20 seconds, if the oscillator which furnishes the timing pulses operates at 1,000 Hz.

A further constant which also must be supplied by printed circuit board 22 is the additional charge, that is the amount which must be added to the portion of the indicator means indicating additional charge upon activation of the corresponding key 17 . This takes place when one of the lines $e00$ to e_n is energized, but will only be explained in more detail later on with relation to the organization of storage 9 .

To summarize, the constant furnishing means, which are exchangeable and externally available, comprise the decoding arrangement 21 , which converts the signals which are furnished by lines $a1$ to $a6$ into the sequential energization of lines $e00$ to e_n in a predetermined order. This energization in turn results in predetermined constants appearing in a predetermined order at the output of the constant furnishing means, namely on lines $i1-i4$. These constant values are then supplied into the computer and storage means 1 .

The indicator means 2 will now be described with reference to FIG. 3. Shown in FIG. 3 are a buffer storage 11 , an address counter 12 , which serves to address the individual storage locations, and a decoding arrangement 13 which comprises a first part $13'$ and a second part $13''$. Further, the indicator means comprise a first indicator section 14 and a second indicator section 15 , each of which provide an indication of five numerals. In the example shown in FIG. 3, the known type of seven segment indicator is used, that is each numeral which is to be indicated comprises seven selectively energizable segments. Thus seven lines are required for the selective energization of a numeral in each indicator position. The seven lines are designated by $b1$ to $b7$ respectively. Each of lines $b1$ to $b7$ is connected with the same segments within each numeral $c1$ to $c10$ of the indicator means 14 and 15 . The decimal numerals $c1$ to $c5$ constitute the indicator portion 15 , while the decimal numerals $c6$ to $c10$ constitute the indicator portion 14 .

Indicator portion 14 serves to indicate the individual fares as long as the taximeter is operating. Indicator portion 15 serves a variety of purposes. While the taximeter is operating, that is while indicator 14 shows the current price or fare, indicator 15 shows the extra charges. When the taxi is standing still and when the taximeter is not operative, indicator portion 15 can be utilized to indicate various accumulated values as for example the total distance travelled while the taxi was occupied, the total distance travelled whether occupied or unoccupied, the total number of additional charges, the total number of fares transported, etc. Thus it is this portion of the indicator which is used to furnish all values which are required in order to effect an accounting between the fleet owner and the driver. These values are normally indicated by mechanical control counters in mechanical taximeters of conventional type.

The individual numerals $c1$ to $c10$ are energized sequentially via lines $d1$ to $d10$ through decoder $13''$. To summarize, the seven information bits which serve to energize the individual segments of numerals $c1$ to $c10$ via lines $b1$ to $b7$ are furnished in parallel by the decoder $13'$ over lines $b1$ to $b7$. However, the signals for

the selection of the corresponding numerals *c1* to *c10* are serially supplied via lines *d1* to *d10*. However, the energization of lines *b1* to *b10* follows at such short intervals that, although pulses are applied to each numeral *c1* to *c10* for only a short time interval the persistence of vision of the human eye causes the indicator to seem to be continuously energized. However, since the indicator is not continuously energized but constantly reenergized, it is required that the values to be indicated are stored in storage 11. This buffer storage may be a matrix having ten storage locations of four bits each, corresponding to the ten numerals *c1* to *c10*. In order to address the storage for storing the data bits, the address counter 12 is provided which is a binary counter and which energizes the storage locations in sequence. For this purpose the output of counter 12 is connected to buffer storage 11 via lines *f1-f4*. These lines are also tied to the input of decoder 13 so that the correct decimal place *c1* to *c10* of the indicator is selected simultaneously with the corresponding storage location in storage 11. The value stored in the storage locations of buffer storage 11 is transferred into the buffer storage via lines *g1* to *g4* which connect buffer storage 11 to storage 9 of the computer and storage means 1. Storage 9 is herein referred to as the first storage means. Normally, the connection is such that determined storage locations of storage 9 correspond to determined storage locations in buffer storage 11, so that any changes which occur in storage 9 are carried out simultaneously in storage 11. However, when one of the keys 18 is operated, that is when an output operation is to take place, the contents of storage 11, which normally comprise the individual fares and the additional charges of said individual fares, is destroyed and those values are entered which are present in the corresponding storage spaces for the total values in storage 9. These values are then transferred to the indicator 15.

A short explanation of the functioning of input register 6 as shown in FIG. 5 follows: this input register comprises eight flip-flops FF0 to FF8 each of which serves the function of an intermediate storage. Each of flip-flops FF0 to FF8 stores a value furnished by a corresponding measuring instrument until these values are called out by the translator portion of the control circuit 3 and transferred to the output stage comprising flip-flop FF0. From there the contents of the flip-flops are then processed in the remainder of the system. Flip-flop FF1 receives a pulse via line *e6* as soon as the computing and storage means has determined that the indicator means have to be advanced. For example, in the example given above, flip-flop FF1 is set as soon as, under fare rate 1, 2,000 distance or timing pulses have been counted and stored in the computer and storage means 1. Flip-flop FF1 is thus not directly connected to the measuring instruments but receives its information from the computer and storage means via the control circuit 3.

Flip-flop FF2 serves to store individual pulses which might be either distance indicating pulses or waiting time indicating pulses, depending on which pulse sequence has the higher rate. These pulses are present at the output of a circuit 7 which, as previously stated, selects the pulse sequence having the higher rate. As shown in FIG. 5 this is accomplished in the following way: First, all distance pulses which arrive at line *e5* are used directly for setting flip-flop FF8. After these pulses have been reduced in rate in accordance with

the tariff or fare rate in effect, they are applied via input *e4* to flip-flop FF9 which is part of the above-mentioned circuit 7. The timing pulses, also after reduction in rate if required in the computer and storage means, are applied via a line *e7* for resetting flip-flop FF9. Line *e7* is not only applied to the reset input of flip-flop FF9, but also to one input of an AND-gate U1 whose other input is the reset output of flip-flop FF9. This output thus carries a "1" signal after a timing pulse has been applied via line *e7* to flip-flop FF9. Flip-flop FF9 is so constructed that the first timing pulse arriving over line *e7* is used to flip the flip-flop from its "0" state to its "1" state. Only the second pulse arriving one line *e7* is thus transmitted through AND-gate U1 so that AND-gate U1 furnishes a pulse to line *e1*. Flip-flop FF9 and AND-gate U1 thus together form the circuit 7 which, in itself is a known circuit and serves to select the higher one of the pulse sequences furnished on lines *e4* and *e7* to constitute the output applied to flip-flop FF2 through line *e1*.

A further flip-flop FF3 serves to store the 100 meter distance pulses. That is the pulses which are used in order to compose the total distance travelled by the taxi or the total distance travelled when in an occupied state. Again, the pulses applied to line *e2* may be pulses whose rate is determined by the constant furnishing means 5 operating in conjunction with the computer and storage means 1. For example if the input constant of the computer 10 is 10 pulses per meter travelled, then the constant furnished must be 1,000, since 100 meters are equivalent to 1,000 pulses.

Flip-flop FF4 is set via line *e8*, when one of input keys 17 is activated to indicate an additional charge. Flip-flop FF5 is set via a line *e9* as soon as the taximeter is put into operation through activation of one of the keys 17. Flip-flop FF6 is set through a signal on line *e0*, as soon as a fare or a distance travelled or a waiting time is reached wherein a change from one fare rate to another is to take place. It should be noted here that lines *e6*, *e4*, *e7*, *e8*, *e9* and *e0* each have an arrow which is to indicate that they are not actually connected with the external measuring elements, but derive their input signals from the computer and storage means 1, as soon as predetermined conditions are achieved. The only input lines which are directly connected to the measuring elements are lines *e5* and *e3*, while line *e2* can be selectively connected either to the measuring element or internally. The synchronizing pulses which, as mentioned above, are furnished via line *e10*, are entered in a multistage shift register 8 and serve to control the individual steps within the cycles of the computer and storage means through use of the control circuit 3. For each received synchronizing pulse, the shift register furnishes a synchronizing pulse over one of its output lines and thus controls the microsteps within the overall cycle.

Flip-flop FF0 serves as the output flip-flop associated with the intermediate storage flip-flops FF1 to FF8. At certain steps within the overall cycle, the condition of flip-flops FF1 to FF8 is interrogated sequentially and if one of these flip-flops is set, its contents is transferred to flip-flop FF0. The signal is then further processed via the control circuit 3 and applied to the computer and storage means 1.

The computer and storage means will now be described in further detail. This will be done with reference to FIG. 4. As shown in FIG. 4 the storage 9 com-

prises 48 storage locations, that is it is capable of accommodating 48 numerals in a binary coded form. Each storage location thus accepts four bits. An address counter 25 serves to address the different storage locations. Since this binary counter has six stages, it is capable of counting from zero to 63. However, its counting capacity is limited to "48," so that after the 48th pulse, the counter is reset to "0." The counter is advanced via line k_0 , which also furnishes the pulses advancing counter 12 associated with storage 11. In response to each pulse received over line k_0 , the counter generates a 6-bit address which addresses storage 9, as mentioned above, via lines a_1 to a_6 . The information in the so-selected storage location is then transferred to the computer means, and specifically to section 26 of a serial adder 26/27 and, if required, via lines g_1 to g_4 into storage 11.

The 47 storage locations in storage 9 are sufficient for storing all variables generated during the formation of the fare and further, generated during the formation of the various totals required for effecting the accounting between the fleet owner and the taxi driver. A possible storage layout is given in the following table: 290

It will be noted that the storage locations a_{00} to a_{04} contain the fare during the individual ride, which fare comprises the base fare and the sum of the fare increments. Similarly, storage locations a_{05} to a_{08} carry the distance reduction rate corresponding to fare rate 1 to fare rate 4, while storage locations a_{09} to a_{12} furnish the constant for the initial distance while flip-flop FF10 is in its first state and furnish a pulse rate reduction of 100:1 when flip-flop FF10 is in the second state. Locations a_{17} to a_{37} are reserved for the storage of the total additional charges, the total distance travelled, the distance travelled while occupied, and the number of trips. These storage locations do not correspond to any constants furnished in the constant furnishing means 5, causing the corresponding output lines of the decoding arrangement 21 in constant furnishing means 5 to be disconnected.

Storage locations a_{43} to a_{45} serve to store the timing pulses which arrive from the timing pulse generator via line e_3 . These pulses have a reduced rate corresponding to the constant furnished by constant furnishing means 5 prior to being applied to input e_7 of circuit block 7.

In order to explain some of the above concepts more clearly, an example will be used. It will be assumed that the waiting time increment, that is the waiting time which is to cause a fare increment, is 20 seconds. Under conditions of fare rate 1 of the above-mentioned example this corresponds to a travelled distance of 200 meters. Thus for each pulse at the output of block 7 to have the same value relative to a fare increment, the distance increment pulses supplied at input e_4 have undergone a pulse rate reduction of 20 to 1. Similarly, for a timing pulse generator which generates 1,000 pulses per second, that is 20,000 pulses in 20 seconds, which corresponds to 2,000 distance increment pulses at fare rate 1. If the 100:1 rate reduction which will take place following stage 7 is taken into consideration, then the timing pulses must undergo a reduction of 10:1. Thus the pulses which arrive at input e_3 are stored in storage location a_{43} to a_{45} . The pulses stored in these storage locations are then compared with the output of constant furnishing means 5 (outputs e_{43} to e_{45} of decoder 21) and a pulse is furnished to line e_7 when the com-

parator shows that the number of pulses stored in locations a_{43} to a_{45} is 10 pulses.

The computer means 10 comprise a first portion 26 and a second portion 27 of a serial adder. Reference to the drawing shows that adder portions 26 accepts the signals from storage 9. For the pulse rate reduction mentioned above, it is seen that adder portion 26 furnishes signals to one input of comparator 28, while the other input of comparator 28 is connected to lines i_1 to i_4 which are the output lines of constant furnishing means 5. Comparator 28 thus continuously compares the number of pulses stored in storage 9 to the number of pulses required until a pulse of reduced rate is to be furnished at the output of comparator 29, namely on line k_1 . From line k_1 the pulses of reduced rate are then applied to the correct one of lines e_1 to e_5 as determined by the control circuit 3.

The control circuit 3 is not discussed in detail here since it is an extremely complicated network. However, it should be clear that this circuit controls the timing of all the components of the taximeter and serves to carry out all the logical decisions generated in the computer 10. Thus the control circuit 3 carries out a number of synchronizing steps which together constitute the overall cycle. Thus in each cycle, counter 25 counts 48 steps, thereby addressing storage spaces a_{00} to a_{47} of storage 9. Counter 12 of course is operated in synchronism with counter 25. However, buffer storage 11 has only 10 storage locations, so that counter 12 counts 4.8 times for each individual runthrough of counter 25. Counter 12 is synchronized to counter 25 at the beginning of each overall cycle.

The adder comprises not only the first and second portions 26 and 27, but also comprises a carry storage 29. The signal generated in the carry storage is also applied to the control circuit 3. It will be noted that adder portion 27 also has inputs connected to the outputs of constant furnishing means 5, namely lines i_4 to i_1 . However, the operation of the adder and the comparator will become clearer with reference to the following example:

At the beginning of each fare activation of the taximeter by actuation of either the keys for fare rate 1, 2, 3, or 4 the base fare is caused to be entered into indicator 14. Since the fare is to be stored in storage locations a_{00} to a_{04} of storage 9, these storage locations must of course be zero at the beginning of each trip and then must be advanced to the base fare, namely \$1.25. The first cycle thus starts with the transfer of the value stored in storage location a_{00} of storage 9 to the portion 26 of the serial adder.

Since the output of counter 25 which is furnished on lines a_1 to a_6 also constitutes the input to the constant furnishing means, line e_{00} of the constant furnishing means is energized simultaneously with the first storage location in storage 9. The value "5" stored in this position of constant furnishing means is thus transferred to portion 27 of the serial adder. At this time flip-flop FF10 is in the condition "10." The control circuit 3 now furnishes a signal via line k_3 which is applied to both portions of the adder. Specifically adder 26 is caused to count forward, while adder 27 is forced to count in the reverse direction. Thus for the first pulse applied on line k_3 the portion 26 is increased by "1," while portion 27 is set to "4." Pulses are now applied by line k_3 until adder 27 is set to "0." At this point no additional pulses are furnished on line k_3 and the con-

tents of adder 26 are transferred into the storage location *a00* of storage 9. Storage location *a01* are not interrogated. The contents of this storage location is transferred to adder 26. Simultaneously line *e01* of the constant furnishing means is energized so that the value "2" is entered into portion 27 of the serial adder via lines *i1* to *i4*. In this case two pulses on line *k3* are required until adder 27 stands at "0" and the numeral "2" is present in adder 26. Again, the contents of adder 26 are now transferred to third location *a01*. The process is now repeated with interrogation of the storage location *a02* and a simultaneous transfer of the numeral "1" from the constant furnishing means via lines *i1* to *i4* to adder 27. Again, after transfer to adder portion 26 by means of the pulses applied on line *k3*, the numeral "1" is entered into storage location *a02* in storage 9. The fourth and fifth place of the base fare each of which is zero in the above example, is then processed in the same fashion. At the end of this part of the cycle the value of \$1.25 is thus stored in storage locations *a00* to *a04* of storage 9. It should also be noted that the same values were simultaneously entered into storage 11. Thus this value is now stored in storage 11 and is then transferred to the indicator means 14 during the remainder of this cycle.

Of course immediately upon the beginning of the trip, that is with activation of any of the keys indicating fare rate 1, etc., the measuring elements have begun to operate. Thus distance pulses are received at input *e5* and timing pulses at input *e3*. Each distance pulse sets flip-flop FF8, each timing pulse flip-flop FF7. Further, flip-flop FF5 is set as soon as any of the keys for fare rates 1 to 4 have been activated. It should be noted here that flip-flops FF1 to FF8 are always interrogated in synchronism with the corresponding storage locations in storage 9. For example flip-flop FF2 is always interrogated simultaneously with storage location *a09*, since, under fare II, the time and distance pulses together form the pulses for determining the fare increment after the base fare has been exhausted and, while the base fare is still in effect, these pulses together constitute the initial distance and must be stored here. Similarly, flip-flop FF3 is interrogated both when storage location *a26* is interrogated and when storage location *a30* is interrogated while the taximeter is operative. When the taximeter is not operative, flip-flop FF3 is only interrogated simultaneously with storage location *a26*. Storage locations *a30* and *a33* change its contents only when the taxi is operating with a fare, while storage positions *a26* to *a29* are advanced whenever the vehicle is in motion.

Following the above-described storing of values in storage locations *a00* to *a04*, storage location *a05* is addressed, simultaneously with flip-flop FF8. Flip-flop FF8 is set as soon as the vehicle has started and the first distance pulse has been received on line *e5*. If flip-flop FF8 is set, a pulse is applied to adder portion 27. Simultaneously the contents of storage location *a05* are transferred into portion 26 and, as previously described, the contents of adder portion 27 are added to the contents of adder portion 26 and the resulting sum transferred back into the storage 9. If a carry-over signal is generated, this signal is stored in store 29 and is added when storing a value in the next subsequent storage location, that is in storage location *a06*. After the processing of storage locations *a07* and *a08*, the contents of storage locations *a05* to *a08* is compared to the

constant furnished at lines *i1* to *i4* of the constant furnishing means 5. If these are unequal, no output is furnished by comparator 28. However, when equality exists (20 distance pulses reached), a signal is furnished on line *k1* at the output of comparator 28 which is applied on line *e4* as well as line *e1*, thereby setting flip-flop FF2 and flip-flop FF9.

Next, storage location *a09* is interrogated. At the very beginning of the trip, of course flip-flop FF2 is not set and storage locations *a09* to *a12* are set to "0." Thus no change occurs in storage locations *a09* to *a12* at the beginning of the trip.

However, if flip-flop FF2 has been previously set, a "1" is added to the contents of storage location *a09* and, simultaneously, a comparison is carried out by comparator 28 between the new contents of storage location *a09* and the constant value furnished at the output *e09* of constant furnishing means 5. As previously mentioned, outputs *e09* to *e12*, when flip-flop FF10 is in its first state, furnish a number corresponding to the initial distance, that is the number "250." Thus, if after a plurality of cycles the value stored in storage locations *a09* to *a12* corresponds to "250," flip-flop FF10 is switched from its first to its second state. However, a pulse for advancing the indicator is applied to flip-flop FF1 only after the contents of storage location *a09* to *a12* have increased to "100" after the above-mentioned change in flip-flop FF10. Only then can flip-flop FF2 be set. Thus after the value "250" has been stored in storage locations *a09* to *a12* following the start of the trip and flip-flop FF10 has changed state, and the storage locations *a09* to *a12* have again reached the value "100" then a pulse is entered into flip-flop FF1. During the next cycle the fare increment is then added to the base fare previously stored in storage locations *a00* to *a04*. That is, the constant furnished at outputs *e00* and *e01* of the constant furnishing means 5, that is the value of \$0.25 is added in storage locations *a00* and *a01*. This addition is also carried out in storage 11 and transferred to the indicator.

During the interrogation of storage locations *a13* to *a16*, it is determined whether flip-flop FF4 is set, that is whether the additional charge key has been activated. If this is the case, a "1" is added in storage locations *a13* to *a16*. The same is true for storage locations *a17* to *a20*, when an additional charge has been entered. A "1" is also added in storage locations *a21* to *a25* when flip-flop FF1 was set in the same cycle, that is when the fare increment of \$0.25 is to be added. A "1" is added in storage locations *a26* to *a29* if flip-flop FF3 is previously set. The same is true for storage locations *a30* to *a33*. A "1" is also added in storage locations *a34* to *a37* since the keys for fare rate 1, 2, or 3 were activated at the beginning of the trip. Storage locations *a43* to *a45* receive an additional "1" if flip-flop FF7 is set, that is if a timing pulse was received at input *e3*. At this point, as explained above, the pulse rate reduction in the ratio of 10:1 takes place before these pulses are applied to input *e7* of stage 7.

It should be noted at this point that the time for one total cycle must be such that even for the fastest input rate at input *e5* flip-flop FF8 can receive a pulse only once per cycle. Since a taxi is allowed to operate at a maximum velocity of 130 kilometers per hour, approximately 400 pulses per second may arrive at input *e5*. The time for the total cycle of the storage must thus be less than 1/400 of a second.

To summarize the functioning of the arrangement of the present invention: At first the base fare is stored in storage locations 100 to a04. The distance pulses are stored in storage locations a05 to a08, while the time pulses are stored in storage locations a43 to a45. Thus, at fare rate 1, that is 2,000 pulses for each advance of the indicator, an output pulse is generated after 20 pulses are stored in storage locations a05 to a08. This pulse is applied to input e4 of the mixing stage 7. Ten pulses are stored in storage locations a43 to a45 until a single pulse is transferred to the input e7 of the mixing stage 7. The pulses at the output of the mixing stage 7, which selects the pulses having the highest pulse rate, are first stored in storage locations a09 to a12. While flip-flop FF10 is in its first state, these pulses are stored until the initial distance as furnished by constant furnishing means 5 has been passed. Thereafter flip-flop FF10 is switched to its second state. As soon as 100 pulses are stored in storage locations a09 to a12, a fare increment of \$0.25 is added to the base fare of \$1.25. In this way a current indication of the total fare is formed which is continuously transferred to storage 11 and thence to the indicator 14. The same is true for additional charges which are entered manually and are continuously transferred from storage locations a1-3-a16 into storage 11 and indicator 15. When the taxi is stopped at the completion of the ride, and the corresponding input key is depressed, no further time pulses are processed. The final fare is indicated on indicator 14 and indicator 15, being the sum of the so-indicated fares. The taximeter is reset to "0" by the activation of the "unoccupied" key which resets storage locations a00 to a16, a38 to a42 and a43 to a47. The values stored in the remaining storage locations are not extinguished, since they are required for effecting the final accounting between the driver and the fleet owner and thus must be maintained passed the individual rides.

If the taximeter is to be equipped for automatic rate changes, then corresponding constant values as applied at the output of constant furnishing means 5 by corresponding activation of lines e38-e42 at the output of decoder 21. These constants may correspond to a particular total fare, a particular distance travelled or a particular waiting time. In this case a taximeter has only one key for "unoccupied" and a second key for "occupied." However, two fare rates are available on printed circuit board 23, that is two different pulse reduction rates are available. If the fare rate is to change after a predetermined total fare has been accumulated during one ride, then the fare as it accumulates is stored not only in storage spaces a00 to a04 but also in storage locations a38 to a42. As the storage 9 is interrogated during each cycle, a comparison is made between the value stored in locations a38 to a42 with the value stored in the constant furnishing means 5, which signifies the fare at which the fare rate is to change. If this value has been reached then the constant furnishing means 5 are switched to the fare rate for fare rate 2, that is instead of lines v1 to v4, lines w1 to w4 are energized so that the indicated fare is advanced not after 2,000 pulses, but already after 1,500 pulses.

The above-described operation is essentially the same as when the key for "fare rate 2" is manually activated. This, too, causes lines w1 to w4 rather than lines v1 to v4 to be energized. Storage locations a05 to a08 then contain the reduction rate for fare rate 2 and a

pulse is furnished to the input of stage 7 after 15 pulses have been received.

Transfer of the contents of storage locations a17 to a37 into buffer storage 11 and thence into the indicator 15 takes place in response to activation of one of keys 18. This, however, can only take place if the taximeter is otherwise not activated. When one of the keys 18 is activated, the corresponding command in coded form is entered into input storage 20 and is further transmitted to the control circuit 3. During the next cycle, the contents of the selected storage locations is transferred to buffer storage 11 and thus to the indicator 15.

The functioning of the computer means was described above as using a serial adder 26/27. This type of adder operates on one place at a time, that is it is not capable of operating on all place values in any number simultaneously. Thus the addition of two numbers, for example as described the addition of the number in part 27 to the number stored in part 26 can take considerable time, especially if a high number of places is to be processed. Since the incoming pulse rate can, however, be very large especially at high taxi velocities, it may be preferable to substitute a full adder for the serial adder 26/27. Such an adder could process two binary numerals in one operating cycle. Building blocks for such adders are commonly available and can be readily substituted for the serial adder described above.

It has been previously mentioned that it is particularly desirable to construct the taximeter in a highly integrated circuit technique, particularly in an MOS technique. In this type of circuitry as generally commercially available, only a given number of terminals can be furnished for any one building block. The taximeter must thus be so constructed that this available number of terminals is sufficient. FIG. 6 shows how the individual building blocks in integrated circuits can be arranged on a circuit board 30 and which terminals are required. Terminals e5, e3, e10 are required for the measuring elements, that is for furnishing the distance pulses, the time pulses and the synchronization pulses. Terminals a1 to a6 are required for addressing the decoder 21 in the constant furnishing means 5. Terminals i1 to i4 are required for the output lines of constant furnishing means 5. Terminals b1 to b7 as well as c1 to c10 on decoders 13' and 13" respectively for connection to indicator 14/15. Indicator 14/15 is of course externally connected. The number of terminals enumerated above comes to 30, so that 10 more terminals remain for assorted purposes such as connecting the power supply. Thus it is possible that the control circuit 3, the pulse rate selector circuit 7, the storage and computer means 1 as well as buffer storage 11, address counter 12, decoding arrangement 13 and storage 20 may all be on one circuit plate which is executed in a highly integrated circuit technique. The externally available constant furnishing means 5, the indicator 14/15, the input and output operation keyboard 4 and the measuring elements are of course externally connectable.

It should further be stated that the constant furnishing means, rather than being constructed in the manner described above can also be executed in a highly integrated circuit technique. Such constant furnishing means are available commercially from a number of firms under the name of PROM (programmable-read-only memory).

While the invention has been illustrated and described as embodied in a taximeter using specific types

of storage means, computing means and external constant furnishing means, it is not to be limited to the details shown, since various modifications and circuit changes may be made without departing in any way from the spirit of the present invention.

Without further analysis, the foregoing will so fully reveal the gist of the present invention that others can by applying current knowledge readily adapt it for various applications without omitting features that, from the standpoint of prior art fairly constitute essential characteristics of the generic or specific aspects of this invention and, therefore, such adaptations should and are intended to be comprehended within the meaning and range of equivalence of the following claims.

What is claimed as new and desired to be protected by Letters Patent is set forth in the appended

1. Electronic taximeter comprising, in combination, first and second measuring means for furnishing, respectively, a first and second pulse sequence signifying distance travelled and elapsed waiting time, respectively; computer and storage means for computing the fare in response to said first and second pulse sequence, said computer and storage means having a first storage means for storing variables required for computing said fare and additional variables for computing totals required for calculating the pay of the taxi driver; electronic indicator means having a plurality of indicator elements, each adapted to furnish a visual output only in the presence of a signal applied thereto; buffer storage means connected to said first storage means and said indicator means, said buffer storage means having a plurality of buffer storage locations corresponding in number to said plurality of indicator elements, each for storing data received from said first storage means and for applying corresponding signals to a corresponding one of said indicator elements when addressed; and control circuit means for cyclically addressing said buffer storage locations in a predetermined order and at a rate sufficient to effect a visually continuous output from each of said indicator elements.

2. An electronic taximeter as set forth in claim 1, wherein said first storage means has a plurality of first storage locations exceeding in number said number of buffer storage locations, said plurality of first storage locations including predetermined first storage locations for furnishing said data to said buffer storage loca-

tions when addressed; and wherein said control circuit means further comprise means for cyclically addressing said first storage locations in synchronism with said addressing of said buffer storage locations.

5 3. An electronic taximeter as set forth in claim 2, wherein said computer and storage means further have means for computing said totals from said variables and storing said totals in said first storage means; further comprising means for storing data corresponding to extra charges to be applied during a trip in corresponding predetermined ones of said first storage locations; wherein said plurality of buffer storage locations includes a first and second set of buffer storage locations, for, respectively, indicating the individual fare and said extra charges when said taximeter is carrying a passenger; wherein said indicator means comprises first and second indicator portions connected, respectively, to said first and second set of buffer storage locations; further comprising a plurality of externally activatable selector elements, each for transferring one of said totals to a buffer storage location in said second set of buffer storage locations when said taxicab is not carrying passengers, whereby said indicator portion further includes a selected one of said totals upon activation of the corresponding one of said selector elements when said taxicab is not carrying passengers.

4. Electronic taximeter as set forth in claim 1, wherein said totals comprise the total fare collected, the number of trips, the distance travelled by the taxi in an occupied state, the distance travelled in an unoccupied state, the total number of additional charges.

30 5. An electronic taximeter as set forth in claim 1, wherein said control circuit means comprise means for furnishing a sequence of control pulses, address counter means connected to said means for furnishing a sequence of control pulses and to said buffer storage means, for counting said control pulses and furnishing address signals addressing said buffer storage locations in response to the so-counted number of pulses, and connecting means for connecting said buffer storage means to said indicator means in such a manner that data in each so-addressed storage location is transferred to the corresponding one of said indicator elements.
